TEMPERATURE RESPONDING DEVICE

Max Hurst, Stuttgart, and Alfred Schweizer,
Vaihingen-on-the-Filders, Germany; vested in
the Alien Property Custodian

Application September 21, 1939, Serial No. 295,990
In Germany September 9, 1938

3 Claims. (Cl. 297—3)

The present invention relates to a device which responds to varying conditions, such as for example, variations of temperature, and which consists for example, of a barrel mounted within a machine element and an adjustment member which abuts against a lever, which is mounted within the same machine element, and which transmits the adjustment movement.

Devices of this type are used for example as thermostats which continually influence the mixture governor of an internal combustion engine, dependently upon the temperature of the supply of combustion air, in such a manner that the fuel supply to the engine decreases as the temperature rises, and vice versa.

As the weakening of the fuel and air mixture can only be taken to a certain point it has been suggested to limit the movement performed by the thermostat as the temperature increases. It has been found, on the other hand, that in many cases no increase of output is produced by a further enriching of the fuel and air mixture after a certain minimum temperature has been passed. On the contrary, when these temperature limits have been passed the thermostat merely produces an excessive richness of the mixture with consequent waste of fuel.

In order to save fuel at temperatures below this limit, the lever equipment according to the invention, is so designed and arranged that it is supported against a stationary part of the apparatus as soon as the temperature falls below a predetermined minimum, so that when the temperature falls still further the lever is unable to follow the movement of the thermostat.

The device disclosed and claimed herein is particularly adapted for use with the fuel-air mixture control means for internal combustion engines disclosed in our application Serial No. 197,456, now Patent No. 2,213,997, to which reference is made as illustrating one practical application or use of this invention.

The invention is more particularly described with reference to the accompanying drawing which shows, by way of example, two forms of construction of the invention and in which:

Figure 1 illustrates the first and Figure 2 the second form of construction.

In Figure 1 the thermostat cartridge 2 is mounted within a threaded nipple 1 secured in the induction pipe 1* of an internal combustion engine and is supported by means of a spring 3 and a ring 4 which is secured within the nipple by a spring ring, in such a manner as to be readily displaceable from the contact position

shown in the drawing. A slotted barrel 5 is screwed on to the threaded nipple 1 and a housing 6 is pushed over the barrel and is held fixed by means of a screw cap 7 which is in threaded engagement with the free end of the barrel 5. Before tightening the screw cap 7, the housing 6, a projection of which engages within the slot 8 of the barrel 5, can be adjusted with the screw cap into any desired position according to the space adjustment required. Within the housing 6 a pin 10 is rotatably mounted and on to it is keyed a lever 11, the movement of which is transmitted through the pin or actuating element 10 for the purpose of adjusting the fuel supply and the mixture of the engine. As the temperature falls, the medium contained in the thermostat cartridge 2 contracts, with the result that the pin or adjustment member 12 is displaced in an inwards direction or to the left in Fig. 1. As soon as a predetermined minimum temperature is reached, the lever 11 which normally abuts against the end face of the pin, rests its nose-like projection 13 against the barrel 14 of the thermostat cartridge and is consequently unable to follow the further movement of the pin in the inward direction. Consequently when this minimum temperature is passed the operation of the thermostat is discontinued, with the result that the fuel and air mixture cannot become any richer.

It is possible to adjust the device to suit various temperatures if the stop projection 13 is designed as an adjustable screw 15, as shown in Figure 2. The adjustable screw is locked in position by means of the nuts 16 and 17.

The examples shown in the drawing are particularly favourable constructions of the device for avoiding the excessively rich fuel and air mixture in the event of the temperature falling below a predetermined minimum. Naturally the rotation of the control lever, or the displacement of the control member, can be limited by a number of other forms of construction.

We declare that what we claim is:

1. A fuel controlling device for internal combustion engines, comprising an actuating element, an adjustment member movable in consequence of temperature variations, a lever connected with the actuating element and operatively connected with said adjustment member so as to partake in the movement of said adjustment member, and means for interrupting said connection between the lever and the adjustment member when the temperature reaches a given value.

2. A fuel controlling device for internal combustion engines, comprising an actuating element, an adjustment member movable in consequence of temperature variations, a lever connected with the actuating element and operatively connected with said adjustment member so as to partake in the movement of said adjustment member, said lever having a noselike projection, and an abutment engageable by said projection for restraining continued movement of the lever with the adjustment member when the temperature reaches a given value.

5

3. A fuel controlling device for internal combustion engines, comprising an actuating element, a barrel, an adjustment member which is movable in said barrel in consequence of temperature variations, a lever connected with the actuating element and adapted to move with said adjustment member, said lever adapted to abut against said barrel to restrain continued movement of said lever with said adjustment member when the temperature reaches a given value.
